BURNISHING MACHINE

Frederick C. Good, Philadelphia, Pa.

Application January 17, 1934, Serial No. 707,032

8 Claims. (Cl. 51—164)

This invention relates to new and useful improvements in burnishing machines and particularly to portable machines for burnishing silverware and like articles.

10 The principal object of the invention is to provide a burnishing machine of the character set forth for burnishing hotel and restaurant table silverware which is portable as a complete unit from place to place.

15 Another object of the invention is to provide a device of the character set forth embodying novel structure permitting the articles of silverware to be discharged therefrom without handling by the operator.

20 A further object of the invention is to provide a device of the character set forth which is constructed and operable in such manner as to not require plumbing connections therewith for drainage and the like.

25 Other features and details of the invention are set forth hereinafter and shown in the accompanying drawing in which:

Fig. 1 is a side elevational view of the device constituting the invention; and

30 Fig. 2 is an end elevational view of the disclosure set forth in Fig. 1.

The present invention is constructed and adapted for use in public dining rooms such as hotels and dining rooms wherein the large number of pieces of table and silverware in use must be cleaned at relatively frequent intervals.

35 Heretofore, the majority of burnishing or polishing machines employed in the cleaning of table silverware as set forth above, have been large, cumbersome machines and of necessity stationary. In addition the majority of these machines comprise generally a horizontal tumbling device mounted in a tub and are operated in such a manner that requires permanent plumbing connections with the various parts thereof for drainage purposes.

40 By the present invention a burnishing machine is provided which is portable as a complete, self-contained unit, and is constructed and operates in a manner and upon a principle which entirely eliminates the necessity for permanent piped connections therewith for drainage or other purposes. The present device is of relatively light weight and may be easily moved from one place of convenience to another for operation. In addition, the invention contemplates the provision of means operatively associated with the burnishing machine to enable the silverware to be discharged from 45 the barrel at will and accordingly eliminates

the heretofore customary but necessary method of removing the same manually.

Referring now more particularly to the drawing, the device made in accordance with the present invention comprises a horizontal supporting member or tray 1 having its edges bent obliquely upward as at 2 to provide side and end walls for the purpose of retaining articles thereon. The tray 1 in the present instance is mounted upon the upper ends of a plurality of legs 3, and as shown in the drawing, a swivel castor or support 4 is mounted in the lower end of each of the legs 3 for a roller 5 which is rotatably mounted in the said swivel supports or castors 4, said roller being fabricated entirely of rubber or provided with a peripheral covering of rubber as may be desired for the purpose of rendering movement of the machine substantially noiseless. A tray or support 6 is mounted in a horizontal position between each of the 75 legs 3 adjacent the lower ends thereof.

In the present instance a pair of upstanding brackets 7, 7 are permanently secured to the upper surface of the tray 1 and these brackets are equally spaced with respect to the longitudinal axis of said tray at opposite sides thereof and adjacent one end of the machine.

The extremities of a pair of parallel arms 9 which project from a hollow casing or housing 10 are pivotally mounted with respect to the brackets 7, 7 by means of a rod or bar 11 which extends through aligned apertures in said arms 9, 9 and brackets 7, 7 as shown in Fig. 2. A support 12 is mounted at one side of the housing or casing 10 and in the present instance an electric or other type of motor 13 is mounted thereon by means of bolts 14. A worm 15 is rotatably journaled in the hollow casing 10 adjacent the upper end thereof, reference being had to Fig. 1, and the outer end of the said worm 15 is directly connected to the shaft 16 of the motor 13 by means of a flexible coupling 17. A worm wheel 18 is fixed on a shaft 19 which is also rotatably journaled in the casing 10 in oil-less bearings 20 and the teeth of this gear 18 mesh with the aforementioned worm 15 which is driven by the motor 13.

100 A tumbling barrel 21 is permanently mounted upon the forward extremity of the shaft 19 and arranged to be rotatably driven thereby through gears 15 and 18 previously set forth. The construction of the tumbling barrel or container 21 and its cover member 22 is substantially the same as shown and described in U. S. Letters Patent 1,911,812 issued to Frederick C. Good, 110

May 30, 1933, and need not be reiterated here.

A rib 23 of substantially U-shape is formed on the inner adjacent faces of the brackets 7, 7 in proximity to the upper end thereof, as shown 5 in Fig. 1 and this rib 23 circumvents the pivotal connection of the arms 9, 9 to the said brackets in spaced relation with respect thereto as shown. When the barrel is in a horizontal position as shown, the inner upper end 23a of the rib 23 10 extends in substantially parallel spaced relation with respect to the adjacent edge surface of the arms 9, 9 to permit the entrance between the latter and the adjacent edge surface of the arms 9, of a space or wedge member 24 pivotally mounted upon one of the inner edges of the arms 9 as at 25 and provided with a lateral 15 projecting handle or actuating member 26. Accordingly, it will be noticed that with the wedge member 24 disposed intermediate the upper 20 inner end 23a of the rib 23 and the particular arm 9, the barrel 21 will be supported with its axis substantially horizontal, and that when the handle 26 is moved in the direction of the arrow in Fig. 2 about its pivot point 25 the wedge or 25 spacer 24 will be displaced from between the rib 23 and arm 9 and permit the barrel 21 and housing 10 to pivot about the bar or rod 11 in a clockwise direction with respect to Fig. 1, so that the opening of the barrel will be declined 30 at an angle sufficient to cause the silverware and burnishing material to be discharged therefrom during the course of usual rotation thereof.

The rear or outer upper end of the rib 23 is inclined upwardly and outwardly at an acute 35 angle as at 23b and the angular disposition of this portion of the rib 23 is such that when the barrel is pivoted about the bar or rod 11 in a counter-clockwise position with respect to Fig. 1, the outer or rear end edge surface of 40 the arms 9 will rest upon this end of the rib 23 and the weight of the barrel will act to maintain itself in this position which approximates the vertical.

In the present instance a container 27 rests 45 upon the tray 1 and is disposed, as shown, below the right-hand or discharge end of the barrel 21. The container 27 is provided with an inner mesh receptacle 28 into which the barrel discharges, in the manner previously set forth, the 50 silverware at the end of a burnishing operation as well as the burnishing materials such as the shot and chemical soap. The mesh of the receptacle 28 should be sufficiently coarse so that when the same is lifted outwardly of the 55 container 27 the shot and other burnishing materials discharged thereinto from the barrel 21 with the silverware will fall or drop therethrough into the container 27 and leave only the silverware in the receptacle or basket 28. The container 27 is provided with a spout or 60 chute portion 29 at one end thereof for the purpose of facilitating return of the burnishing materials to the barrel 21 for a succeeding burnishing operation.

In operation of the device the pivotally 65 mounted wedge or spacer 24 controls the movement of the barrel to various positions. When the barrel is lifted or pivoted to a substantially vertical position, as previously described, it balances itself and when dropped or pivoted to a horizontal position as shown, the spacer 24, in the position shown in the drawing, retains it in that position until displaced, at which time the barrel will drop to an angle below the horizontal 70 for discharge of the silverware and burnishing 75 materials which is accomplished by allowing the barrel 21 to continue rotating.

While the features and details of the invention have been specifically set forth for the purpose of description, it is not intended that the invention be wholly limited thereto except such as is not within the scope of the annexed claims.

What I claim is:

1. In a burnishing machine, a tray supported on wheels for portability, brackets secured to the upper surface of the tray, a housing, a tumbling barrel rotatably mounted on said housing, and arms projecting from the housing, said arms being pivotally connected to said brackets to permit the barrel and housing to be pivoted at will to both substantially vertical and horizontal positions. 85

2. In a burnishing machine, a tray supported on wheels for portability, brackets secured to the upper surface of the tray, a housing, a tumbling barrel rotatably mounted on said housing, arms projecting from the housing, said arms being pivotally connected to said brackets to permit the barrel and housing to be pivoted at will with respect to said brackets, and means on said 90 brackets for positively limiting pivotal movement of said housing and barrel. 100

3. In a burnishing machine, a tray supported on wheels for portability, brackets secured to the upper surface of the tray, a housing, a tumbling barrel rotatably mounted on said housing, arms projecting from the housing, said arms being pivotally connected to said brackets to permit the barrel and housing to be pivoted at will with respect to said brackets, means on said 105 brackets for positively limiting pivotal movement of said housing and barrel, and means operatively associated with said last-mentioned means for controlling the pivotal movement of the barrel and housing to at least one of two predetermined positions. 110

4. In a burnishing machine, a tray mounted on wheels for portability, brackets mounted on the upper surface of the tray, a housing, a tumbling barrel rotatably mounted on said housing, 115 arms extending from said housing, and a bar extending loosely through the brackets and said arms to permit the housing and barrel to be pivoted at will with respect to said brackets. 120

5. In a burnishing machine, a tray mounted on wheels for portability, brackets mounted on the upper surface of the tray, a housing, a tumbling barrel rotatably mounted on said housing, arms extending from said housing, a bar extending respectively through the said brackets 125 and arms to permit the housing and barrel to be pivoted at will with respect to the brackets, and means for positively limiting the pivotal movement of the housing and barrel. 130

6. In a burnishing machine, a tray mounted on wheels for portability, brackets mounted on the upper surface of the tray, a housing, a tumbling barrel rotatably mounted on said housing, arms extending from said housing, a bar extending respectively through said brackets and 135 arms to permit the housing and barrel to be pivoted at will with respect to the brackets, means for positively limiting the pivotal movement of the housing and barrel, and means operatively associated with said last-mentioned 140 means for controlling the pivotal movement of the barrel and housing to at least one of two predetermined positions. 145

7. In a burnishing machine, a tray supported on wheels for portability, brackets secured to 150

said tray, a housing pivotally connected to said brackets, a tumbling barrel rotatably mounted on said housing, and means positively limiting pivot of the barrel and housing within a pre-determined arc.

8. In a burnishing machine, a tray supported on wheels for portability, brackets secured to said tray, a housing pivotally connected to said

brackets, a tumbling barrel rotatably mounted on said housing, means positively limiting pivot of the barrel and housing within a predetermined arc, and means operable to control the pivotal movement of said housing and barrel to at least one of two predetermined positions. 80
